UNITED STATES PATENT OFFICE.

ALFRED L. CLARK, OF DUBUQUE, IOWA.

WINDOW-SCREEN.

SPECIFICATION forming part of Letters Patent No. 292,410, dated January 22, 1884.

Application filed June 12, 1883. (No model.)

To all whom it may concern:

Be it known that I, ALFRED L. CLARK, of Dubuque, in the county of Dubuque and State of Iowa, have invented a new and useful Improvement in Window-Screens; and I do hereby declare that the following is a full and exact description of the same, reference being had to the accompanying drawings, and to the letters of reference marked thereon.

10 My invention relates to that kind of window-screens in which the screen is wound upon a spring-roller attached to the window-sill, and has its upper edge secured to the lower rail of the lower sash, so that in raising and lowering 15 the sash the screen will also be raised and lowered, and always cover the opening formed by raising the sash.

The object of my invention is an improvement upon such window-screens, with the view 20 of making them more effective and convenient; and to accomplish these objects I have found it essential, first, to provide a convenient receptacle for the spring-roller upon which the screen is wound when not in use; 25 second, to provide means whereby a continual tension is put upon the screen, whether wound upon the spring-roller or not; third, to provide a catch whereby the screen is automatically attached to the sash, and which allows 30 of the ready detachment of said screen from said sash; fourth, to provide suitable guides in which the edges of the screen move when said screen is raised or lowered, the use of which guides renders the movement of the 35 screen certain and even; and, fifth, to provide means whereby the screen will not be affected by currents of air or like causes and the edges of the same withdrawn from the guides above referred to.

40 To the accomplishment of the above the invention consists—

First. Of a suitable box or receptacle consisting of a top and front plate, and provided at each end with suitable metal end pieces, 45 which serve as bearings for the spring-roller, and which are suitably bent at their lower ends to afford ready and convenient means for attaching this box to the window-sill.

Second. Of a metal catch formed of a strip 50 of metal, bent as shown, and provided with a cross-piece, with which pins secured to the window-sash make contact. This catch is se-

cured to the upper end of the screen, and upon the top of the box which incloses the spring-roller I provide a pin, which holds the 55 said catch in position. These parts are so arranged that when the window is lowered the screen is automatically secured thereto, and is raised and lowered therewith, the parts being capable of ready detachment.

6c Third. Of suitable guides secured to the sides of the window-casing, and consisting each of a flat metal strip and a similar strip bent lengthwise at its center, the two forming a guide in which the edges of the screen 65 move when said screen is raised or lowered, thus obtaining an even movement for the screen and effectually excluding insects of all kinds.

Fourth. Of one or more metal rods secured 70 to the screen and extending from side to side of the same. These rods wind around the spring-roller when the screen is not in use, and serve to prevent any sagging of said screen caused by air-currents or otherwise.

75 For the better understanding of the invention and in order that those skilled in the art may make and use the same, reference will be made to the accompanying drawings, which form part of this specification, and in which—

80 Figure 1 is an elevation of a window-casing, showing my improvements; Fig. 2, a vertical section taken on line *xx* of Fig. 1; Fig. 3, a view in detail of the box inclosing the spring-roller and screen and also the catch for attaching the screen to the window-sash; and Fig. 4, a sectional view of the spring-roller with screen removed, and showing the means for attaining a continual tension on the same; Fig. 5, a view in detail of the metal guides. 85 Fig. 6 is a section on the line *yy* of Fig. 1, and Fig. 7 is a section illustrating the position of the strips *ff'* to form the screen-guides.

90 Like letters refer to corresponding parts in each of the views.

95 In the drawings, A represents the window-casing, B the upper, and C the lower, window-sash, and D the window-sill.

100 Situated upon the sill D is the box or casing, in which the spring-roller hereinafter referred to is mounted. This box, which is shown clearly in Fig. 3, consists of a top piece, E, front piece, E', and end pieces, E''. The top and front pieces I prefer to make of wood, and,

if desired, they may be formed of a single piece. The end pieces, E^2 , are formed, preferably, of metal, and are bent at their lower ends to form flanges a , through which pins a' are passed to secure this box to the window-sill. When it is not desired to use the screen—as, for instance, in winter—this entire box, together with the spring-roller F and screen G , can be removed by simply withdrawing the pins a' . The end pieces, E^2 , are provided at or about their centers with suitable openings, into which are inserted the ends of the shafts c , upon which the spring-roller F is revolved. The spring-roller F is of ordinary construction, with the exception that at a point near one end it is provided with a hole, b , Fig. 4, a corresponding hole being produced in one of the shafts c , upon which the roller revolves and into which a pin, d , is inserted, to prevent the spring 20 e from unwinding until the screen G is attached to said roller. When this screen has been securely attached to the roller, as shown, the pin d is removed and the screen is subjected to a constant tension.

Secured in any desirable manner to the upper end of the screen G , and extending entirely across the same, is a rod, H , to the center of which is secured the catch, to be hereinafter referred to. The ends of this rod H enter the metal guides I , secured to the side of the window-casing, as also do the rods H' , &c., which are secured to the screen at any desirable intervals, these last-named rods winding around the spring-roller when the screen is not in use. Instead of these rods H' , it may be found advantageous to secure to each edge of the screen G a thin strip of steel, said strips winding around the spring-roller with the screen and answering the same purpose as said rods H' .

The metal guides referred to consist each of a flat strip, f , secured to the window-casing and in the groove in which the window-sash moves and protrudes out beyond said groove. At a suitable distance from this strip f is secured a strip, f' , bent at right angles lengthwise, the two strips forming the desired guide, and being secured to the window-casing in any desirable manner. The strip f' extends from the window-sill up to the highest point to which the lower sash can be raised; but the strip f' extends only from the top of the box in which the spring-roller is inclosed up to the same point as does the strip f .

When the box above referred to is placed in position on the sill, the inner edges of the end pieces, E^2 , come in contact with the strip f and prevent said box from being pushed in too far.

The catch before referred to as being secured to the center of rod H , attached to the top of the screen, consists of a piece of metal bent, as shown, to form the two arms g and the cross-bar h , said arms g being bent at right angle near their upper ends. That portion 65 of the arms g which are bent as above described carries the cross-bar and rests upon

the top piece, E , of the box or casing which incloses the spring-roller. The top piece, E , is provided, as shown, with a pin or knob, i , against which the cross-bar h impinges to hold the catch in position.

Secured to the arms g at the point shown is a cross-bar, j , the object of which will be stated.

The lower bar, J , of the lower window-sash, C , is provided with two or more pins or knobs, k k , below each of which is formed on said lower bar the inclined plane $k' k'$.

When the several parts are in their proper positions and the lower window-sash is lowered, the inclined planes $k' k'$ are brought in contact with the cross-bar j , and the catch is forced back until the pins or knobs k k pass said cross-bar, when the catch is brought forward again by the tension to which the screen is subjected continually. The window is then raised, and the cross-bar j is brought under the pins k k , and the screen is raised with said window, covering the open space and excluding insects of all kinds, the screen being prevented from sagging by the bars H H' , &c., and being rendered uniform in its movement by the metal guides situated on the side of the casing.

When it is desired to raise the window without raising the screen, the catch is withdrawn from contact with the pins j by a motion of the hand drawing out the cross-bar h .

Throughout the foregoing description I have described and illustrated the spring-roller and the box in which it is inclosed as situated on the window-sill and upon the inside of the window-casing; but I do not wish to confine myself to this arrangement, as it will be evident that said parts might be arranged at the top or bottom, and upon the inside or exterior of the window-casing, as may be desired.

Having thus described my invention, what I claim as new therein, and that for which I desire to secure Letters Patent, is—

1. The combination, with a spring-roller, of a window-screen adapted to be automatically attached to the window-sash by means of a catch secured to the free end of said screen, and engaging with projections upon the lower bar of said sash when the latter is raised or lowered, substantially as and for the purpose set forth.

2. The combination, with the catch constructed and attached to the window-screen and its casing, as described, of the lower window-sash, C , provided with the pins k k and inclines $k' k'$, substantially as and for the purpose set forth.

3. The combination, with a spring-roller and a window-screen wound thereon, of a box for inclosing and supporting the same, said box consisting of the top and front pieces, E E' , and end pieces, E^2 , bent at their lower ends to form flanges a , substantially as described, whereby, with the aid of pins or other suitable

means, said box, with its inclosures, is adapted to be removably attached to the windowsill, as set forth.

4. The combination of spring-roller F, window-screen G, wound on said roller, window-sash C, and bars H H', as and for the purpose set forth.

5. The combination of spring-roller F, window-screen G, window-sash C, bars H H', and

metal guides I, consisting each of the strips 10 f f', arranged as described and shown.

In testimony whereof I affix my signature in presence of two witnesses.

ALFRED L. CLARK.
